FOUNTAIN PEN INK GUARD AND CAP

Solomon M. Sager, Hubbard Woods, Ill.

Application June 28, 1937, Serial No. 150,670

15 Claims. (Cl. 120—42)

It has been found that when fountain pens are not in use and the writing end thereof is enclosed by the ordinary fountain pen cap that excess ink remaining in the feed bar and on the pen point accumulates around the outer end of the fountain pen section, with the result that the excess ink collects at the end of the section and flows into the fountain pen cap. Due to the leakage of ink from the fountain pen into the fountain pen cap, the interior of the cap and the exterior of the fountain pen section become stained with excess ink so that when the fountain pen is being used, the hands of the user become stained with the excess ink.

For the purpose of obviating the leakage of ink from the feed bar and pen point to the exterior of the fountain pen section and the interior of the fountain pen cap, this invention has been devised for the purpose of providing a fountain pen with a tapered or frusto-conical shaped ink guard extension on the outer end of the fountain pen barrel or barrel section adapted to tightly interfit with a threaded end of a liner or sleeve engaged in the closed end of a fountain pen cap to produce a double seal between the ink guard and the liner sleeve so as to provide an air tight chamber enclosing the feed bar and pen point, so that any excess ink remaining in the pen point or in the feed bar is prevented from leaking into the cap affording an arrangement whereby any excess ink is permitted to gradually flow back through the feed bar grooves into the ink chamber of the fountain pen barrel.

It is an object of this invention to provide an improved type of fountain pen wherein an inner sleeve in the fountain pen cap is adapted to coact with an ink guard on one end of the fountain pen barrel when the cap is in closed position, to provide a seal at the inner end of the guard and at the outer end thereof preventing the leakage of ink into the fountain pen cap and around the exterior of the ink guard and the section portion of the barrel.

Another object of the invention is the provision of a fountain pen wherein an ink guard with inclined walls is formed on one end of the fountain pen barrel for receiving a portion of an inner sleeve of the fountain pen cap and to provide a double seal between the sleeve and the ink guard when the cap is in closed normal position over the writing end of the fountain pen.

It is also an object of this invention to provide an improved type of fountain pen wherein the section end of the ink barrel is provided with an improved type of apertured ink guard and where-

in the apertured fountain pen cap is provided with an inner sleeve, which when the cap is engaged on the barrel will insure either a double seal between the ink guard and the sleeve, or a positive seal at either the inner end or the outer end of the ink guard with one of the two stop shoulders formed on the inner sleeve of the cap.

It is furthermore an object of this invention to provide an improved fountain pen wherein the barrel has a stop ring or flange formed on a portion thereof to the outside of which an improved ink guard with inclined walls is integrally formed for the reception of an inner sleeve secured within the fountain pen cap to normally provide a double seal between the ink guard and the inner sleeve of the cap when the cap is in closed position over the barrel of the fountain pen, or provide at least one positive seal between the ink guard and the cap inner sleeve should one of the two seals fail to become effective.

It is also an important object of this invention to provide an improved type of fountain pen wherein the barrel has a section integrally formed near one end thereof with said section terminating at a stop ring or flange to the outside of which is integrally formed a tapered or frusto-conical shaped ink guard having an inner seal shoulder and an outer seal shoulder for coaction with a plurality of sealing shoulders provided at one end of an inner sleeve or cap secured in the closed end of a main fountain pen cap which is engageable over the ink guard end of the barrel to permit the two sealing shoulders of the cap inner sleeve to have sealing contact with the seal sealing shoulders of the ink guard and also a locking engagement with said ink guard to hold the fountain pen cap secured in position over the writing end of the fountain pen when the fountain pen is not in use.

Other and further important objects of this invention will be apparent from the disclosures in the specification and the accompanying drawing.

The invention in a preferred form is illustrated in the drawing and hereinafter more fully described.

On the drawing:

Figure 1 is an elevational view of an improved fountain pen embodying the principles of this invention with one end of the fountain pen cap broken away to indicate the tight seal between the fountain pen ink guard and the inner sleeve of the cap.

Figure 2 is an enlarged longitudinal detailed section taken on line II—II of Figure 1 showing

parts in elevation and part of the barrel broken away to illustrate the double seal between the ink guard and the inner sleeve of the fountain pen cap.

5 Figure 3 is an enlarged fragmentary detailed sectional view of a portion of the view illustrated in Figure 2 to show the details of the double seal between the ink guard and the fountain pen cap, and the threaded connection between the cap sleeve and the ink guard for holding the cap releasably engaged over the writing end of the fountain pen when the same is not in use.

Figure 4 is an end view of the ink guard end of the fountain pen barrel.

15 Figure 5 is an end view of the open end of the fountain pen cap.

Figure 6 is an enlarged fragmentary sectional view similar to Figure 2 but showing only a single inner sealing contact between an end surface of 20 the cap inner sleeve and the inner shoulder of the ink guard.

25 Figure 7 is an enlarged fragmentary detailed section similar to Figure 3 but showing only a single sealing contact between a stop shoulder forming a part of the inner sleeve of the fountain pen cap and an outer end surface of the fountain pen ink guard.

As shown on the drawing:

30 The reference numeral 1 indicates a fountain pen barrel, one end of which is tapered to form an integral section 2, the outer end of which terminates at a stop ring or flange 3, which separates the section 2 from an ink guard integrally formed on the outer end of the section 2. The ink 35 guard comprises a frusto-conical or inwardly tapered body portion 4 having an inclined recess or groove 5 formed in the outer end thereof leaving an outer stop shoulder or seat 6 between the groove and the outer wall of the ink guard body.

40 Forming part of the fountain pen construction and projecting through the ink guard 4 and into the section 2 of the ink barrel is an ink feed bar 9 and a pen point 10. Provided in the wall of the ink guard 4 is a suction reducing or vacuum 45 breaking air port 11, the purpose of which will hereinafter be described.

For the purpose of closing the writing end of the fountain pen when the fountain pen is not in use, a cap 12 is provided which is open at one 50 end while the other end is closed by an end wall 13. Provided in the wall of the fountain pen cap 12 is an air port 14 located opposite the ink guard 4 when the cap is in position to close the pen. By referring to Figures 3 and 4, it will be noted 55 that the air ports 11 and 14 are both adapted to communicate with the space between the exterior of the ink guard 4 and the inner wall of the fountain pen cap 12 when the cap is engaged over the writing end of fountain pen. Secured in the 60 closed end of the fountain pen cap 12 is an inner sleeve or inner cap 15 which is closed at one end to seat in the closed end 13 of the fountain pen cap. The opposite end of the inner sleeve or inner cap 15 is open and is provided with an end sealing surface or valve seat 16 which registers with a shoulder 17 provided within the cap 12. The sealing shoulder or valve seat 16 of the sleeve 15 is adapted to have a sealing contact with the sealing shoulder 6 at the outer end of the ink guard 4, when the cap is engaged over the writing 70 end of the fountain pen as illustrated in Figure 2. The inner sleeve or inner cap 15 is provided with an exteriorly threaded collar or shank 18 adapted for threaded engagement with the threaded portion 7 of the ink guard 4. The end of the

threaded collar or shank 18 terminates in a sealing shoulder or valve seat 19 provided for sealing contact with the inner sealing shoulder or valve seat 8 provided within the ink guard 4.

Referring to Figures 2 and 3, it will be noted 5 that when the fountain pen is not in use and the cap is engaged over the writing end of the fountain pen that the threaded shank 18 forming part of the inner sleeve or inner cap of the main cap 12 threads into the threaded portion 7 of the 10 ink guard 4 thereby providing a means for securing the cap 12 in position on the main body or barrel of the fountain pen to enclose the ink guard, the feed bar, and pen point. The threaded shank 18 is threaded into the threaded portion 15 15 7 of the ink guard until the sleeve valve seat or shoulder 16 seats against the outer sealing shoulder 6 of the ink guard and until the end sealing shoulder or valve seat 19 of the inner sleeve 15 seats against the inner sealing shoulder or valve 20 seat 8 of the ink guard. It will thus be noted that with an accurate construction of the ink guard and the inner sleeve of the cap 12 that a double seal is provided between the inner cap and the ink guard. When it is desired to use the fountain 25 pen, it is only necessary to rotate the cap 12 to first break the double seal between the inner sleeve and the ink guard at which time the suction action within the inner sleeve 15 is broken by the provision of the air port 11, and the suc- 30 tion action or partial vacuum between the cap 12 and the exterior of the enclosed section end of the fountain pen barrel is also broken by the provision of the air port 14. By the provision of the air ports 11 and 14, any suction action which 35 might arise with the removal of the cap is broken, so that there is no tendency of the ink from the interior of the fountain pen to be sucked or drawn out of the feed bar. The air ports also facilitate 40 drying out of the interior of the cap around the enclosed exterior portion of the section 2 and the ink guard 4, and also act to obviate the tendency of sweating of the enclosed parts of the fountain pen when the cap 12 is in closed position.

In case the threaded shank portion 18 of the 45 inner sleeve 15 of the fountain pen cap is too long, only an inner seal will be provided between the end of the shank portion 18 and the sealing shoulder 8 of the ink guard, as clearly illustrated in Figure 6, since the sealing shoulder 16 is not 50 permitted to contact the outer sealing shoulder 6 of the ink guard.

Where the threaded neck or collar 18 of the inner sleeve 15 of the fountain pen cap is slightly 55 shorter than it should be, an outer seal only is provided between the sealing shoulder 16 of the sleeve 15 and the sealing shoulder 6 of the ink guard, for the reason that the end sealing shoulder 19 of the extension 18 is not permitted to contact or seat against the inner sealing 60 shoulder 8 of the ink guard. It will thus be noted that in a normal condition with the proper construction of the ink guard and the inner sleeve of the fountain pen cap that a double seal is provided between the ink guard and the inner 65 sleeve of the cap, and that in case of any slight discrepancy in the length of the threaded collar or shank 18 of the inner sleeve 15, there will always be either an outer seal or an inner seal 70 between the ink guard and the inner sleeve of the fountain pen cap, as illustrated in Figures 6 and 7 of the drawing.

When the cap 12 is in proper closed position engaged over the writing end of the fountain pen, the collar 18 of the inner sleeve 15 engages in the 75

ink guard 4 to form a substantially perfect locking seal therewith, locking out any possible air circulation, thereby preventing evaporation or leakage of the ink and the elimination of sweating around and on the pen point.

When the fountain pen cap 12 is removed from the body or barrel of the fountain pen to permit use of the fountain pen, attention is called to the fact that when any ink accumulates at the outer end of the ink guard 4 on the sealing shoulder 6, that such excess ink is permitted to rapidly flow inwardly on the inclined wall of the groove 5 into the chamber provided in the main body portion of the ink guard 4. The inclined groove 5 also permits the return of ink into the ink guard and back into the fountain pen when the cap 12 is engaged over the writing end of the fountain pen.

It will, of course, be understood that numerous details of construction may be varied through a wide range without departing from the principles of this invention, and it is, therefore, not the purpose to limit the patent granted hereon otherwise than necessitated by the scope of the appended claims.

I claim as my invention:

1. A fountain pen including in combination a barrel, an apertured ink guard on one end thereof formed with a plurality of sealing shoulders, an apertured cap, and a sleeve secured in said cap and formed with a plurality of sealing shoulders to sealingly contact the shoulders of the ink guard when the cap is engaged on the barrel over the ink guard.

2. A fountain pen including in combination a barrel, an ink guard on one end thereof formed with a plurality of sealing shoulders, said ink guard having an air port therein, a cap provided with an air port, and a sleeve secured in said cap and formed with a plurality of sealing shoulders to sealingly contact the shoulders of the ink guard when the cap is engaged on the barrel over the ink guard with the cap air port adjacent the ink guard air port.

3. A fountain pen comprising a barrel, a section on one end thereof, a stop flange formed on the section, a feed bar and pen point projecting into said section, an ink guard formed on said section to the outside of said flange and surrounding the feed bar and pen point, said ink guard having an air port therein and also formed with inner and outer sealing shoulders, a cap having an air port therein, and a sleeve secured in said cap and formed with outer and inner sealing shoulders for respective sealing contact with the inner and outer sealing shoulders of the ink guard to provide a double seal between the ink guard and said sleeve when the cap is engaged on the barrel to close the writing end of the fountain pen with the cap air port positioned adjacent the ink guard and near the air port formed therein.

4. A fountain pen comprising a barrel, a section on one end thereof, a stop flange formed on said section, a feed bar and pen point projecting into said section, a tapered ink guard on said section to the outside of said flange and surrounding and free from contact with said feed bar and pen point, said ink guard having an air port formed therein and also having inner and outer sealing shoulders formed thereon, a cap for removable engagement on the barrel to enclose the writing end of the fountain pen, and a sleeve secured in said cap and formed with a plurality of sealing shoulders for seating against

the sealing shoulders of the ink guard when the cap is in closed position to provide a double seal between the fountain pen and the cap thereof.

5. A fountain pen including in combination a barrel, an ink guard formed thereon and having an air port therein, and a cap for removable engagement on the barrel and provided with an air port to be positioned in communicating relationship with the air port in the ink guard when the cap is in closed position.

6. A fountain pen including in combination a barrel, a section integrally formed on one end thereof, a peripheral flange formed on the outer end of the section, and a tapered ink guard formed on said section adjacent the stop flange, said ink guard having an air port therein and also having an inclined recess in the outer end thereof.

7. A fountain pen including in combination a barrel, a section integrally formed thereon, a peripheral stop flange integrally formed on the end of the section, an ink guard integrally formed on the section adjacent the peripheral flange, said ink guard having an air port therein and also provided with an inclined groove in the outer end thereof, a cap having an air port therein, and a sleeve secured in said cap for sealingly interfitting with the ink guard when the cap is in closed position on the barrel to position the cap air port in communicating relationship with the air port in the ink guard.

8. In a fountain pen, a tapered ink guard having an air port therein and an inclined groove in the outer end thereof.

9. A fountain pen including in combination an outwardly flaring ink guard having an air port therein and also having an inner stop shoulder and an outer stop shoulder formed thereon, a cap for removable engagement on the fountain pen to enclose the ink guard, said cap having an air port therein adapted to be positioned in communicating relationship with the air port in the ink guard when the cap is in closed position, and a double shouldered sleeve in said cap for air tight sealing contact with the shoulders of the ink guard when the cap is in closed position, to obviate ink leakage and sweating and the elimination of air circulation within the closed fountain pen.

10. A fountain pen body construction comprising a barrel, a section integrally formed on one end thereof, a stop flange integrally formed on the end of the section, and a tapered ink guard integrally formed on the end of the section to the outside of the stop flange, said ink guard having an air port formed therein and an inclined groove in the outer end thereof and also being provided with inner and outer stop shoulders.

11. A fountain pen comprising a barrel, a tapered section integrally formed on one end thereof and provided with internal threads, said ink guard having an air port therein and an ink receiving recess in the outer end thereof, said recess having an inclined wall for facilitating the return of ink into the ink guard, said ink guard also having inner and outer sealing shoulders formed thereon, an apertured cap for the fountain pen, and a sleeve secured in said cap and formed with an exteriorly threaded portion and with a plurality of sealing shoulders, said threaded portion of the sleeve adapted to be threaded into the threaded portion of the ink guard when the cap is moved into closed position to bring the stop shoulders of the cap sleeve into sealing

contact with the shoulders of the ink guard to provide a double seal within the fountain pen.

12. A fountain pen including in combination a barrel, an internally threaded tapered apertured ink guard integrally formed on one end thereof and provided with an inner and an outer stop shoulder, an apertured cap for removable engagement on said barrel to enclose the ink guard, and an externally threaded sleeve secured in the cap and provided with inner and outer stop shoulders, said externally threaded sleeve adapted to be threaded into the ink guard to hold the cap locked in position with either one or both of the stop shoulders of the sleeve engaging one or both of the stop shoulders of the ink guard to provide a seal between the sleeve and the ink guard when the cap is in closed position.

13. A fountain pen including in combination a barrel, a cap for removable engagement on one end of the barrel, said cap having an air port therein, an apertured ink guard formed on the barrel to be enclosed by the cap, and means in said cap for releasably locking the cap in posi-

tion on the barrel by a locking engagement of said means with the ink guard.

14. A fountain pen including in combination a barrel, an ink guard integrally formed thereon and provided with an air port, a cap removably engaged on the barrel to enclose the ink guard, said cap having an air port therein positioned adjacent the ink guard when the cap is in closed position, and means in the cap for releasable locking engagement with the ink guard to hold the cap secured in position.

15. A fountain pen comprising a barrel, an apertured ink guard formed on one end thereof, an apertured cap for removable engagement on the barrel to enclose the ink guard, and a sleeve member secured in the cap for locking engagement with the ink guard to form either a multiple or a single air tight sealing contact between said sleeve and the ink guard when the cap is in a completely closed position with respect to the fountain pen barrel to obviate ink leakage and sweating.

SOLOMON M. SAGER.
